UNITED STATES PATENT OFFICE.

ABRAHAM M. YEAKEL, OF PERKASIE, PENNSYLVANIA.

STEM WINDING AND SETTING WATCH.

SPECIFICATION forming part of Letters Patent No. 350,407, dated October 5, 1886.

Application filed May 8, 1886. Serial No. 201,565. (No model.)

To all whom it may concern:

Be it known that I, ABRAHAM M. YEAKEL, a citizen of the United States, and a resident of Perkasie, in the county of Bucks and State of Pennsylvania, have invented certain new and useful Improvements in Watches; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a face view of a watch with the 15 face removed, showing my improved stem setting and winding mechanism. Fig. 2 is a similar view showing the device applied to a hunting-case watch. Fig. 3 is a sectional view 20 of the pendant. Fig. 4 is a perspective view of the separate parts of the pendant. Fig. 5 is a view of the winding and setting mechanism seen from the rear side or in a direction opposite to the direction seen in Fig. 1, and Fig. 6 is a perspective detail view of the case- 25 spring for a hunting-case watch.

Similar letters of reference indicate corresponding parts in all the figures.

My invention has relation to that class of stem winding and setting watches in which 30 the cog-wheels or pinions which engage the cog-wheels upon the post of the mainspring and the cog-wheels of the hands are journaled at the ends of a yoke having a common cog-wheel engaging the cog-wheels at the ends and 35 engaging the setting and winding pinion, and in which this yoke may be tilted, so as to engage either the winding or setting mechanism; and it consists in the improved construction and combination of parts of the same, as 40 hereinafter more fully described and claimed.

In the accompanying drawings, the letter A indicates the front plate of the casing of the works, and B is a cog-wheel secured upon the post of the mainspring, which is journaled in 45 the said plate to one side.

C is the cog-wheel which meshes with the pinion upon the post of the minute-hand of the watch, and which is provided with the pinion D, which meshes with the cog-wheel E 50 upon the sleeve of the hour-hand, and this cog-wheel is placed at the opposite side of the

stem of the minute-hand to the cog-wheel upon the stem or post of the mainspring.

A yoke, F, has a central circular aperture, G, with which it is pivoted upon a circular 55 disk, H, secured to the front plate of the case, and this disk is considerably thicker than the yoke, having a cogged ring, I, turning upon it, the said ring having outwardly-projecting cogs and inwardly-facing beveled cogs J, as plainly 60 seen in Fig. 5. This yoke is formed with inwardly-projecting pins K and L at its ends, and cog-wheels M and N are journaled upon these pins, bearing against the face of the front plate with their inner faces, and meshing with 65 the central cogged ring. The cog-wheel M meshes normally with the winding cog-wheel, while the other cog-wheel, N, may mesh with the cog-wheel of the setting mechanism when the yoke is tilted, so as to disengage the cog-wheel from the winding-wheel and force it toward the setting cog-wheel. 70

A spring, O, is secured at one end near the edge of the front plate of the casing, and the inner free end of this spring bears against a 75 pin, P, projecting inward from the yoke above the cog-wheel which meshes with the setting mechanism, forcing that end upward and forcing the end having the winding-wheel downward, so as to mesh with the wheel upon the 80 post of the spring, and this end is prevented from being tilted too far down by a projecting lug, Q, upon the end of the yoke bearing against a screw or stud, R, upon the front plate. The cogged ring meshes with a beveled pinion, S, 85 secured upon the lower end of a stem, T, or shaft, the upper end of which is formed into either a polygonal tap or a polygonal socket.

A pin, U, slides through a perforation in the upper portion of the side of the casing and 90 in an eye, V, within the casing, and the lower end, W, of this pin is bent forward and slides in a slot, X, in the front plate of the casing bearing against the upper edge of the end of the yoke having the setting-wheel, while the 95 upper end of the pin projects through said perforation in the side of the casing.

The case-center Y of the watch has the inner or lower end, Z, of the pendant A' secured into it, and this pendant is formed with sockets or recesses in its side to receive the ends of the bow-ring E', while its upper end, C', is re- 100

duced and provided with a removable flange or ring, D'. A ring, E', fits with its central perforation upon the reduced end of the pendant, and has its upper reduced and screw-threaded end F' bearing against the removable flange, while its lower end is recessed and slides with a lip, G', upon the outer side of the pendant. A coiled spring, H', is secured around the reduced portion of the pendant, resting with its lower end in an annular recess, I', surrounding the lower end of the reduced portion, and resting with its upper portion in the recess formed by the lip of the ring E', forcing the same upward against D', which is preferably clinched or riveted upon the end of the reduced portion of the pendant. A cap, J', fits with its internally screw-threaded lip upon the screw-threaded upper reduced portion of the ring E', and the upper end of a stem or key-pipe, K', is secured to the inner side of the top of the cap projecting down through an axial perforation, L', in the pendant. The lower end of this stem or key-pipe fits in or upon the socket or tap projecting up through the side of the casing for the works, so that the works may be wound or set by the turning of the stem or key-pipe and its cap and ring, and the stem or key-pipe is provided with a flange, M', which bears against the upper side of a perforation, N', in the case-spring O', which is secured inside of the case-center, and has its outer end bearing against the pin projecting out through the side of the inner casing. It will thus be seen that when the cap and ring are revolved the mainspring may be wound, the winding-wheel being placed with its teeth at such an angle to the teeth of the wheel B upon the mainspring-arbor that when the winding-wheel is revolved backward its teeth will slip over the teeth of the other wheel, while its teeth will engage the teeth of the other wheel when wound forward, the teeth of the winding-wheel sliding in between the teeth or cogs of the wheel upon the mainspring-arbor when revolved forward, while when revolved backward the sides of the teeth will strike the ends of the teeth or cogs of the wheel upon the mainspring-arbor obliquely, so that they will slide over them, the spring at the other end of the yoke allowing the cogs of the wheels to slide over each other, while they will be forced back, meshing with each other by the spring at the same time.

When the watch is to be set, the cap and ring are forced inward against the coiled spring, and the flange or collar of the stem or key-pipe will bear against the case-spring, which again in turn will bear against the end of the pin, which will tilt the yoke with its inner bent end, causing the setting-wheel to mesh with the setting mechanism, so that by turning the cap and the stem or key-pipe the cogged rim and the setting-wheel may be revolved. The spring bearing against the stud at the end of the yoke having the setting-wheel will raise that end of the yoke and will raise the pin, so

that it will again project when the pressure is removed from the cap.

In a hunting-case watch the case-spring is preferably constructed as shown in Fig. 6 and in Fig. 2, the free end of the spring being split longitudinally, and the upper portion of the split end is provided with an outwardly-projecting latch-lip, P', which engages the lip of the cover, while the lower portion, Q' of the split end is thicker or stiffer than the upper end and carried beyond the end of the same.

The flange or collar upon the stem or key-pipe only bears against the edge of the perforation of the lower and longer portion of the spring, and when the said stem or key-pipe is pushed in the lower stiffer end will draw the upper and weaker portion with it, causing the latch-lip to be disengaged, and when the stem or key-pipe is pushed still farther in the upper portion will catch with its latch-lip against a portion of the inside case or other portion of the casing, stopping it, while the lower portion will be pushed sufficiently far in to allow the hands to be set.

The coiled spring and the case-spring bearing up against the ring, the upper end of this ring will be forced perfectly tight against the flange or collar at the upper reduced end of the pendant, forming a dust-tight joint, and the lip of the swivel-ring sliding tightly against the outer side of the pendant will assist in making the pendant perfectly dust and water tight, excluding all dust and dampness, so that if the casing of the watch is perfectly tight no dust or dampness will be admitted through the pendant, and the watch will be perfectly protected.

The pendant may be used with open-faced as well as with hunting-case watches, and may be used in stem-winding watches as well as in key-winding watches, as the pendant is useful as well for simply opening the case of a watch as for winding it, or for opening the case and for winding it, forming in all cases and for all purposes a tight joint for the stem or key-pipe sliding within the pendant.

Although the pendant is particularly adapted for the winding and setting mechanism shown and described, the said mechanism may be operated by other pendants having similar functions—viz., being capable of having a cap or head revolved and pushed in. The works may be very easily removed from a casing having this pendant, as it is only necessary to clasp the ring firmly and thereupon turn the cap backward, when the cap will be unscrewed and the stem or key-pipe may be removed, when the works may be taken out in the usual manner, and when the works are to be inserted into the case the stem or key-pipe may be fitted into its proper socket or upon its proper tap, whereupon by revolving the ring and holding the cap firmly the ring may be screwed into the cap, drawing the cap downward and securing the same.

The case-spring will assist the coiled spring

in holding the ring up against the flange or collar upon the reduced portion of the pendant, and if the coiled spring should by accident be disabled the case-spring will be able 5 to perform its duties, together with its own, so that the pendant will remain operative.

By this construction of the winding and setting mechanism the hands may be set by simply pushing the cap and ring inward, avoiding 10 the necessity of pushing a setting-lever in or drawing it out, as in usually-constructed stem winding or setting watches, avoiding trouble and preventing the possibility of keeping the setting-lever in position after the hands 15 have been set, in which position the works will be stopped.

Having thus described my invention, I claim and desire to secure by Letters Patent of the United States—

20 1. In a stem winding and setting watch, the combination of a yoke having a cogged wheel or ring at its pivotal point meshing with a pinion upon a winding-stem, and having a winding-wheel at one end meshing with the central wheel or ring and with a wheel upon the mainspring-arbor, and a cog-wheel for setting the hands at the other end meshing with the central wheel or ring, a spring bearing upward upon the setting end of the yoke, a case-spring having a perforation near its end for the passage of the setting-stem, a setting-stem or key-pipe having a cap at its upper end and fitting in a socket or upon a tap of the upper end of the inner stem, and having a flange or 25 collar bearing against the outer side of the case-spring, and a pin projecting with its outer end through the side of the inside casing and bearing with that end against the end of the case-spring, and having its inner end bent outward and bearing against the setting end of the yoke, as and for the purpose shown and set forth.

2. In a hunting-case stem winding watch, the combination of a setting mechanism having an upwardly-projecting pin and winding mechanism having an upwardly-projecting revolving stem, a case-spring having a perforation near the free end and having that

end split longitudinally, having the upper portion cut off immediately beyond the perforation and provided with an upwardly-projecting latch-lip, and the lower portion extending beyond the upper portion, bearing against the reciprocating pin, and being stiffer than the upper portion, and a winding and setting stem or key-pipe having its inner end fitted to the stem and having a shoulder or flange bearing against the outer side of the lower portion of the spring, as and for the purpose shown and set forth. 55

3. The combination of a watch-pendant having its upper end reduced and provided with a removable collar or flange, a swivel-ring fitting and turning upon the reduced portion of the pendant having a reduced upper portion 60 screw-threaded and bearing against the collar or flange and having a downwardly-projecting lip sliding upon the pendant, and a cap having a stem projecting through the pendant and having the inner side of its downwardly-projecting flange screw-threaded and fitting upon the threaded upper portion of the swivel-ring, as and for the purpose shown and set forth. 70

4. The combination of a watch-pendant having its upper end reduced and provided with a removable collar or flange and having an annular recess around the lower end of the reduced portion, a swivel-ring having an upper reduced and screw-threaded portion and having a lip 75 sliding upon the outside of the pendant having the upper end bearing against the collar or flange, a coiled spring resting in the annular recess and bearing against the lower recessed end of the swivel-ring, and a cap having a stem passing through the pendant and having the inner side of its downwardly-projecting flange 80 screw-threaded and fitting upon the threaded upper portion of the swivel-ring, as and for the purpose shown and set forth. 85

In testimony that I claim the foregoing as my 90 own I have hereunto affixed my signature in presence of two witnesses.

ABRAHAM M. YEAKEL.
